(57) CLAIM

The ornamental design for side skirt for an automobile, as shown and described.

DESCRIPTION

FIG. 1 is a perspective view of a side skirt for an automobile, the perspective view taken from in front of and above the side skirt;

FIG. 2 is a plan view thereof, taken from a side of an automobile;

FIG. 3 is a top view thereof;

FIG. 4 is a bottom view thereof;

FIG. 5 is a front end view thereof, taken from a front of an automobile;

FIG. 6 is a rear end view thereof, taken from a rear of an automobile; and,

FIG. 7 is a perspective view thereof, attached to an automobile.

The broken line showing of an automobile is for illustrative purposes only and forms no part of the claimed design. The broken line showing of any internal surfaces of the side skirt forms the bounds of the claimed design but not part of the claimed design.
